AIR COOLED TIRE RASPING WHEEL

Alton E. Tobey, 2203 Mission St.,
Santa Cruz, Calif. 95060

Filed Jan. 4, 1971, Ser. No. 103,946

Term of patent 14 years

Int. Cl. D15—99

U.S. Cl. D37—1

FIG. 1

FIG. 3

FIG. 2

FIG. 4

FIG. 5

FIG. 6

FIG. 1 is a perspective view of an air cooled tire rasping wheel showing my new design.

FIG. 2 is a perspective view of the side of the wheel reversely of that shown in FIG. 1.

FIG. 3 is a plan view of the wheel shown in FIGS. 1 and 2.

FIG. 4 is a view similar to FIG. 1 but of a modified form of my new design.

FIG. 5 is an elevational view of each side of the wheel shown in FIG. 4.

FIG. 6 is a plan view of the wheel shown in FIGS. 4 and 5.

I claim:

The ornamental design for an air cooled tire rasping wheel, substantially as shown and described.
